UNITED STATES PATENT OFFICE.

ASHTON O. C. AHRENDTS, OF NILES, OHIO, ASSIGNOR TO THE ATLAS CHINA COMPANY,
OF NILES, OHIO, A CORPORATION OF OHIO.

DESIGN FOR DECALCOMANIA SHEET.

Application filed June 24, 1924. Serial No. 9,954. Term of patent 3½ years.

To all whom it may concern:

Be it known that I, ASHTON O. C. AHRENDTS, a citizen of the United States, residing at Niles, in the county of Trumbull and State of Ohio, have invented a new, original, and ornamental Design for Decalcomania Sheet, of which the following is a specification, reference being had to the

accompanying drawing, forming a part thereof.

The figure is a plan view of a portion of a decalcomania sheet embodying the design.

I claim:—

The ornamental design for decalcomania sheet as shown.

ASHTON O. C. AHRENDTS.
